16 Claims. (Cl. 250—8)

The invention relates to a telegraph system provided with means for effecting repetition or reiteration of the signals. Systems of this type are known and their purpose is to render harmless, for the greater part, disturbances of any origin but of the same character, for example, disturbances which only cause additional current impulses.

Our system is particularly adapted to printing telegraph transmission and reception via radio channels where the usual five-unit code is employed. This code, as is well known, is made up of different permutations of elemental signals commonly termed "marking" and "spacing" elements. There are 32 possible combinations of such elements in a five-unit code. The invention is adapted also for use with other signaling codes. Thus, generally speaking, if each character signal consists of n -units then the 20 number of possible permutations equals 2^n .

In order that signals comprising five-unit code elements may be accurately received and decoded despite mutilation by atmospheric disturbances and fading, we have found that a continuous repetition of the signals is essential. Our apparatus is, therefore, designed to cause the transmitter to repeat or reiterate the signals, while the receiver is caused to store the signals for certain fixed intervals of time. The stored 30 effects of the repeated signals are then combined and caused to control the operation of the receiving printer so as to print the characters of a message without repetition.

It is within the scope of our invention to provide transmitting and receiving apparatus suitable for repeating the signals either once or several times. The periodicity of repetition being fixed, there is very small likelihood that a disturbing impulse would also be repeated with the 40 same periodicity.

There are two possible methods of carrying out our invention. By one method the receiving printer is caused to print in accordance with signals whose marking elements are each repeated the proper number of times. By the 45 other method the receiving printer is caused to function in response to the reception of signals whose spacing elements are each repeated the correct number of times.

With the system described in the foregoing, it is therefore possible to render harmless either additional current impulses or missing current impulses.

By additional current impulses are to be understood disturbances which produce an addi-

tional marking current at the receiver, and by missing current impulses are to be understood disturbances which result in the non-appearance of the marking or spacing current (that is to say, fading phenomena). 5

If a repeating system be imagined which has for its sole object to nullify the effect of additional marking current impulses, then each marking current impulse that drops out, due to fading, will lead to the printing of an incorrect 10 character. Conversely, in a repeating system which is adapted merely to supply missing marking current impulses, an incorrect character will be printed by each additional current impulse which results from static or other disturbances. In this connection, it is immaterial whether the missing current impulse or the additional current impulse occurs in the first signal transmitted or in one of the repetitions. Repeating systems are hence more sensitive to disturbances whose influence is not rendered harmless than systems without signal repetition, i. e. repetition increases the possibility of the occurrence of such disturbances. 15

The systems described hereinbefore cannot 20 therefore be used for communications in which disturbances of both characters (i. e. both additional signals and missing signals) may occur. An example of such a communication is a short-wave radio communication. 25

The system according to the invention provides the possibility of rendering harmless to a great extent both the influence of the additional current impulses and that of the missing current impulses. This is attained by making the influence of the missing current impulses on the receiver equal to that of the additional current impulses. 30

In order to more clearly set forth the present invention, it will be described in connection with 40 the accompanying drawings in which:

Figure 1 is a diagrammatic showing of a transmitting circuit corresponding to the present invention.

Fig. 2 is a diagrammatic showing of a receiving 45 circuit adapted to cooperate with the transmitting circuit shown in Fig. 1.

Fig. 3 is a diagrammatic showing of a modified form of transmitting circuit.

Fig. 4 is a diagrammatic showing of a receiving 50 circuit adapted to cooperate with the circuit of Fig. 3, and

Fig. 5 shows both transmitting and receiving features of a signal reiterating system as used in simplex telegraphy. 55

Referring to Figures 1 and 2 of the accompanying drawings, a method according to the invention will be described by way of example, wherein both types of disturbances exert the same influence on the receiving reiterating system.

In Figure 1 we show a conventional code transmitter for a printing telegraph system. A code unit repeating system is placed under control of the code transmitter. This repeating system is here shown diagrammatically and will be hereinafter described upon reference to Fig. 3. Output signals from the repeating system are fed to a transmitting relay 9 having an armature 44, a marking contact 40 and a spacing contact 42. The contact 40 is connected to a tone-frequency generator 41 which produces a tone of a certain frequency indicative of a marking impulse. Contact 42 is likewise connected to a tone frequency generator 43 which produces a different frequency indicative of a spacing impulse. The armature 44 connects through the primary of a transformer 45 to ground. The secondary of the transformer 45 may be connected to a modulator at which carrier frequency energy is combined with the tone frequencies. Thence the signals are passed through an amplifier of any suitable description to a transmitting radio antenna.

Fig. 2 shows apparatus at a receiving station for utilizing such signals as may be transmitted from the system shown in Fig. 1. The tone frequency currents are derived from the radio receiver 46 by means of a first detector. These currents are then filtered separately through two filters 47 and 54. Filter 47 is tuned to pass the marking tone frequency as generated at 41 (Fig. 1), while filter 54 passes both marking and spacing tone frequencies. The output from filter 47 is then fed to a rectifier 48, while the output of the filter 54 is fed to rectifier 55.

Amplifier stages 48' and 55' are respectively connected to the rectifiers 48 and 55. The connections are such that when signaling energy is passed through either one of the rectifiers it causes its associated amplifier to block. The normal current flow through the amplifier 48', which occurs in the absence of a signal energizes the relay winding 49 so as to hold its armature 51 against the contact 52. Likewise in the presence of signaling energy through the rectifier 55 its associated amplifier 55' is caused to block, while in the absence of signals of both marking and spacing frequencies the relay winding 56 is maintained energized by normal current flow through the amplifiers 55'.

One important advantage to be derived from the use of the blocking amplifiers 48' and 55' is that the relays 49 and 56 are actuated by current impulses of constant amplitude irrespective of the strength of the incoming signals.

The operation of the system shown in Fig. 2 may be understood from the description immediately following.

When a marking impulse is received the rectifier 48 passes the signal to its associated amplifier 48', causing this amplifier to block. The normal flow of current through the tubes 48' is interrupted and the coil 49 de-energized. The armature 51 is then attracted by the biasing coil 50 and contacts with the negative contact 53, thereby impressing a marking impulse on the repeating and translating system shown in detail in Fig. 4.

Since the wide band filter 54 also passes the

same signal through the rectifier 55, the amplifiers 55' are also caused to block and the relay coil 56 de-energized. The armature 58 is then drawn up against the positive contact 59 by the biasing coil 57. There is, however, no transfer of energy through the armature 58 at this time because the circuit thereof is dead-ended at the open contact 52.

Upon receipt of a spacing signal which has a tone frequency corresponding to that of the generator 43 (Fig. 1) the filter 54 will pass this spacing signal, while the filter 47 will not pass the same. Under these conditions the relay coil 49 will remain energized while the relay 56 de-energizes. The biasing coil 57 will then pull up the armature 58 so as to pass positive current through the closed contacts 59, 58, 52 and 51 to the signal repeating system of Fig. 4.

An incoming impulse produced by an atmospheric disturbance would normally influence both rectifiers 48 and 55. The result obtained is, therefore, the same as though a marking impulse were received, but such a disturbance being of a casual nature would not be likely to be repeated with the same effective periodicity that is provided for the signal impulses. Therefore, the disturbing impulse itself will be nullified by the operation of the signal repeating and translating system presently to be described.

When fading occurs there will be a normal flow of current through both amplifiers 48' and 55', thereby causing relay coils 49 and 56 to become simultaneously energized. In this case the signal repeating and translating system will be fed with a negative marking impulse, irrespective of whether a marking or a spacing signal was sent. This effect is produced by the passage of current from the negative contact 60 through armature 58, contact 52 and armature 51.

It will thus be seen that the repeating system receives negative marking current not only in response to the marking signals and to atmospheric disturbances, but also in response to fading phenomena.

The relays 49 and 56 (Figs. 2 and 4) are each provided with a biasing winding 50 or 57, through which direct current of adjustable intensity is always flowing, and the purpose of which is to put the tongues 51 and 58 against the contacts 53 and 59 when the windings 49 and 50 56 are not energised. Of course this result may be attained by other means, for example springs, or by means of the spacing current.

In Figures 1 and 2, it has been assumed that the carrier frequency is modulated alternately with two audio-frequencies. The arrangement of the circuits may also be so designed, however, that under the influence of the transmitting relay 9 high frequency marking and spacing waves are alternately transmitted by the radio-transmitter.

The method described in the foregoing for reversing the influence of the missing current impulses in a repeating system may likewise be employed if, according to the invention, several channels of transmission are formed simultaneously through one radio-transmitter, that is to say, if several messages are transmitted simultaneously through one radio-transmitter. Such transmission is of particular importance in the use of repeating systems on account of the considerably smaller transmission capacity. If the normal transmission, in which one or more frequencies are used for each channel, is employed for this purpose, difficulties arise because in this

case a separate fading-reversing device has to be provided for each channel.

According to the invention, this disadvantage is obviated by means of a circuit arrangement in which only one frequency is employed at any moment for the simultaneous transmission of several messages through one radio-transmitter. With such a construction, only one reversing device is employed for all the channels, while there is also the important advantage that the entire power of the transmitter is available for each channel at any time.

The circuit arrangement according to the invention will be described by way of example with reference to Figures 3 and 4. Figure 3 represents the transmitter end and Figure 4 the receiver end. At the transmitter end there are two telegraph systems I and II. For these two telegraph systems working independently of each other there are now four different possibilities, viz:

1. System I gives marking current, system II gives spacing current.
2. System I gives marking current, system II gives marking current.
3. System I gives spacing current, system II gives marking current.
4. System I gives spacing current, system II gives spacing current.

As shown in Figure 3, each system is provided with two transmitting relays 61, 62 and 63, 64 respectively connected either in series or in parallel. The marking contact 65 of the relay 61 is connected through the output transformer of an audio-frequency generator 66 to the spacing contact 67 of the relay 63. The spacing contact 68 of the relay 61 is connected through the output transformer of an audio-frequency generator 69 to the marking contact 70 of the relay 63. Also, the marking contact 71 of the relay 62 is connected through the output transformer of an audio-frequency generator 75 to the marking contact 73 of the relay 64, and the spacing contact 74 of the relay 62 is connected through the output transformer of an audio-frequency generator 72 to the spacing contact 76 of the relay 64. The tongues of the relays 61 and 62 are connected together and to one terminal of a transformer 71. This transformer is connected to the line leading to the radio-transmitter. The other terminal of the transformer 71 is connected to the two tongues of the relays 63 and 64. Since the relays work in pairs simultaneously, it follows from Figure 3 that there is always one, but never more than one, audio-frequency generator connected to the line leading to the radio-transmitter.

By tracing the connections through contacts of relays 61, 62, 63 and 64, it will be seen that the different tone frequencies from the generators 66, 69, 72 and 75, may be utilized to represent different combinations of marking and spacing signals simultaneously transmitted via the two channels I and II as follows:

Channels		Contacts closed		Tone frequency	Generator
I	II				
Mark	Space	65	67	n_1	66
Mark	Mark	71	73	n_2	75
Space	Mark	68	70	n_3	69
Space	Space	74	76	n_4	72

At the receiver end (Figure 4) are provided two radio-receivers 105 and 106. Each receiver receives one side band of the incoming modulated carrier wave and feeds the telegraph signals to the corresponding low-frequency part of the circuit. In the drawings, the two low-frequency parts are shown adjacent each other. They are exactly alike and also cooperate in the same way with the rectifiers 79, 80 and 81 to be described hereinafter.

The object of using two radio-receivers is to mitigate the influence of fading phenomena. This measure, however, is not essential, and it is also possible to employ only one radio-receiver.

The low frequency amplifiers 36 both feed through a transformer 107 to three low frequency filters 38 and one filter 54. The filters 38 are designed to pass respectively the frequencies n_1 , n_2 , and n_3 , each corresponding to one of the possible combinations of signals (except the fourth) sent via channels I and II. Filter 54 passes all four of the signaling frequencies.

Five separate rectifiers 79a and 79b, 80a, 80b and 81 are preferably provided for receiving the output energy from the respective filters. These rectifiers may be similar to the rectifiers 48 and 55 as shown in Fig. 2 and they are caused to control three blocking amplifiers 82, 83 and 84 so as to operate the relays 49a, 49b and 56. Fig. 4 shows the interconnections from the filters through the rectifiers and amplifiers to the relays as follows:

Signal frequency	Rectifier	Amplifier	Relay	Derived signal	
				Channel I	Channel II
n_1	79a (79b)	82	49a 49b	Mark Mark	Space
n_2	180a	83	49b	Mark	Mark
n_3	80b	83	49b	Space	Mark
n_4	81	84	56	Space	Space

Since filter 54 passes all four frequencies, the associated amplifier 84 will normally remain continuously blocked and the relay 56 will remain de-energized. It will become energized only on the occurrence of fading. Hence the relay armature 58 remains normally in contact with the positive (spacing) contact 59 so as to feed a positive impulse through either or both of the armatures 51 to the repeating systems of channels I and II according to the respective energizations of relays 49a and 49b. The spacing signal is, therefore, normally produced on channel I if both frequencies n_1 and n_2 are absent, and on channel II if both frequencies n_2 and n_3 are absent. In the event of a fading condition relays 49a, 49b and 56 will become energized simultaneously, thereby delivering negative marking impulses to the repeaters of both channels. On the occurrence of atmospheric disturbances or static impulses amplifiers 82 and 83 will both become blocked and the relay armatures 51 will be drawn against the negative (marking) contacts 53 by the biasing coils 50, thus delivering marking current to the repeaters of both channels. Of course, the number of the individual channels may be increased. Thus, for example, three or more channels may be employed, all operating with the full power of the transmitter. In this case, the number of frequencies required will be correspondingly higher for three channels, for example, 8 frequencies, and generally for n channels, 2^n frequencies.

In the foregoing, it has been assumed that

synchronism is maintained between the automatic devices for the signal repetition at the transmitter and receiver ends of the communication.

In reiterating devices employed in combination with means which render the influence of the missing current impulses equal to that of the additional current impulses, special measures are necessary, however, for maintaining synchronism, because fading generally lasts considerably longer than a disturbance which causes an additional current impulse.

Our transmitting system for automatically repeating the signals is illustrated in Fig. 3. The cooperating system for storing the received signals and combining the repetitions thereof is illustrated in Fig. 4. The synchronization between the transmitter and receiver is obtained by well known methods as used, say, in multiplex systems having rotary distributors. In Figs. 3 and 4 the invention is illustrated in respect to a diplex printing telegraph system, that is to say, where two communications channels are provided for simultaneous transmission of signals in one direction. From the description to follow it will be obvious, however, that simplex transmission and reception would be available by merely utilizing sufficient apparatus to accommodate a single communications channel, as shown in Figs. 1 and 2.

Figure 3 shows the transmitting ring of the distributor of a multiplex telegraph system. This ring, in the present example, is sub-divided into four sectors 1, 2, 3, 4 and is also provided with two contact segments 100 and 101 for synchronizing. Only one group of the five contact segments of each sector is shown with the pertaining parts. This group serves for repeatedly transmitting one of the five elements of which each signal is composed. The device works as follows:

If the contact device 5 of the signal transmitter is connected to the positive terminal of the battery, as shown in the drawings, and hence spacing current is sent, then when the brush 6 on its first revolution passes over the corresponding contact segment 7, the corresponding polarized relay 8 in series with the transmitting relays 61 and 62 will be energized. The tongue of the relay 8 will thereby be connected to the positive or spacing contact. When the brush 6 on the second revolution, passes over the contact segment 11 of the sector 3, the relay 12 will be energized, whereby its tongue 13 will be connected to the positive or spacing contact or will remain there if it was already in contact with the said contact. In this case, the transmitting relays 61 and 62 will again be energized. On the third revolution of the brush 6, on passing over the contact segment 14, the relay 15 will be energized and its tongue 16 will be connected to its positive or spacing contact. Now the transmitting relays 61 and 62 again receive spacing current. Finally, on the fourth revolution of the brush 6 and on contacting the contact segment 17, the transmission relays 61 and 62 will again be energized with spacing current. Hence the transmitting relays 61 and 62, on the revolution of the brush 6, will receive in succession all the current impulses which have been established at the individual contact segments of the distributor by the signal transmitter in co-operation with the tongues of the repeating relays.

The receiving system shown in Fig. 4 comprises apparatus for the simultaneous reception of sig-

nals on two channels I and II. In the description to follow, however, it will suffice to explain one unit of the repeating system since this unit is duplicated for as many channels as would be provided. Fig. 4, therefore, complements the showing of Fig. 2 insofar as a simplex system would require a simplex repeating device for storing the signals before translating the same. On the other hand, Fig. 4 illustrates a diplex receiving system adapted to cooperate with the diplex transmitter of Fig. 3.

There are two receiving relays 18_I and 18_{II} either of which may be supplied with marking or spacing current according to the reception of marking and spacing signals pertaining to each of the channels I and II. Further reference, therefore, to the relays 18_I and 18_{II} will be made with respect to either relay alone as relay 18. One of these relays will follow the movements of the transmitting relays 61 and 62 (Fig. 3) which, it was noted, are operated conjointly. The other of the relays 18 operates in accordance with the transmitter relays 63 and 64, also operating conjointly. The purpose of the relays 18 is to supply marking or spacing current to the repeating relays which are associated with the receiving ring of the distributor. The segments of this distributor are shown in developed diagram. The ring is subdivided into four sectors, each sector containing five segments corresponding to the five units of a code signal. Each of the contact segments of the ring, as in the ordinary multiplex telegraph apparatus, is preferably made somewhat shorter than the corresponding contact segments of the transmitter ring. That is to say, the intervening insulation segments are made somewhat longer. The purpose of this is to render the reception immune to slight deviations from synchronism between the transmitter and receiver. The segment 102, however, is made to comprehend an arc approximately equal to the sum of the segments 100 and 101 of the transmitter. Segment 102 is used for synchronizing and controls a correction device in conventional manner.

In the position shown in the drawings, the tongue of the receiving relay 18 is connected to the spacing contact (+). As soon as the brush 19, which rotates synchronously with the brush 6 at the transmitting station, passes over the receiver segment 20 corresponding to the transmitter segment 7, the repeating relay 21 is energised so that its tongue 22 is connected to the spacing contact (+). On the next revolution, the brush 19 on contacting the contact segment 23, will energise the relay 24 through the tongue 22, the tongue 25 being thereby connected to its spacing contact (+). As soon as, on the third revolution, the brush 19 comes into contact with the contact segment 26 the relay 27 will be energized and the tongue 28 will be connected to its spacing contact. Finally, on the fourth revolution, when the brush 19 is passing over the contact segment 29, the output relay 30 will be energized and the tongue 31 of this relay will be connected to its spacing contact, whereby a signal element will be supplied to the receiving apparatus. It follows from the foregoing that when, at the receiver end, one of the repeating relays has once had spacing current, the operation of the succeeding repeating relays is completely independent of the receiving relay 18, since each of the further repeating relays receives current directly from the spacing contact of the tongue of the preceding repeating relay.

11, however, the receiving relay 18 receives marking current, so that its tongue is connected to the contact marked minus (—), the repeating relays receive marking current one after the other, but 5 now through the marking contact of the receiving relay 18.

The result hereby attained is that atmospheric disturbances no longer cause mutilation of the received signals.

10 In the foregoing description of Figs. 3 and 4 the novel features of our invention have been explained when applied to one particular embodiment of our apparatus wherein two separate communications channels I and II are available, 15 and wherein the reiterating systems for the two channels are controlled by proper selections from four tone frequency sources at the transmitting end and corresponding tone frequency filters at the receiving end, one of the receiving filters, 20 however, being adapted to pass all four tone frequencies. In a more simple application of the reiterating systems either of two tone frequencies may be employed as shown in Fig. 1, and the system may be operated as a simplex reiterating system as shown in Fig. 5. Furthermore, the 25 reiterating system may be employed where the carrier wave is simply keyed on and off and where the employment of any tone frequency may be immaterial. Fig. 5, therefore, furnishes a comprehensive picture of the reiterating system as a whole, and the operation both at the transmitting end and at the receiving end may be readily understood from the foregoing description which is more particularly directed to Figs. 3 and 4. The operation is still further described 30 in respect to either of the Figs. 4 or 5 as follows:

According to the foregoing description it will be understood that when signals are mutilated by atmospheric disturbances the receiving apparatus 40 is caused to apply negative marking impulses to the repeating apparatus additional to those of the signal itself. Also the dropping out of any of the original marking impulses due to fading is compensated by the introduction of marking impulses at the receiver. In all probability, however, the mutilations of a given signal would not 45 be repeated. Hence, the repeating system is designed to control the receiving printer according to the exact repetitions of marking signals and only when each of these repetitions takes place 50 the full number of times.

Let it be assumed by way of illustration that each signal is to be repeated four times. Take one signal, for example, which is composed of the following elements: Marking, Spacing, Spacing, Marking, Marking. In the following tabulation the elements will be designated as follows: M=Marking, S=Spacing, A=Atmospherics. In 55 the four repetitions of the signal originally transmitted as MSSMM, mutilated signals may appear 60 at the receiver as follows:

First transmission MASMM
Second transmission MAAMM
Third transmission MASMM
Fourth transmission MSAMM

65 The occurrence of the atmospheric impulses A will, of course, cause marking current at the receiver where spacing current ought to have appeared. If the disturbing atmospherics occur 70 while marking current was originally transmitted, they will not cause mutilation of the signal. On the other hand, if fading occurs, then a marking current impulse will be introduced at the receiver in response to a fading condition. 75 In the case above illustrated the repeating ap-

paratus will so function that the successive transmissions of signals will be stored as follows:

First transmission MMSMM
Second transmission MMMMM
Third transmission MMSMM
Fourth transmission MSMMM

5

Since in the second and third positions there are no instances of four repetitions of the marking signal, spacing signals will be applied to the printer. The marking signals being repeated four times, will also be applied to the first, fourth and fifth positions. Hence, the correct signal as originally transmitted will be applied to the printer. 10

An advantage of the described system resides in the fact that a transmitter repeating system and a receiver repeating system can be easily coupled to a common driving member. Moreover, by providing more than one disc several complete repeating systems may be operated. The distributors may for instance be provided with sixfold distributor discs, so that three channels may be operated per disc, each with one repetition, or two channels each with two repetitions. When employing fourfold distributor discs two channels may be operated each with one repetition or, as described in connection with Fig. 3, one channel with three repetitions. 15

It will be readily understood by those skilled in the art that the methods employed as herein described are applicable not only to synchronous multiplex systems, but also to so-called start-stop telegraph systems. In other words, it is immaterial whether the distributors as shown, for example, in Figs. 3, 4 and 5 are caused to rotate continuously or intermittently. The principles involved in the operation of the reiterating system are the same in either case. 20

Various modifications of our invention will suggest themselves to those skilled in the art in view 25 of the foregoing description. The invention, therefore, is to be considered as having all the breadth which is permitted by the scope of the claims. 30

What we claim is:

1. A multiple unit code telegraph system comprising means for producing marking signals of one frequency, means for producing spacing signals of a different frequency, repeating means for controlling the operation of the signal producing means to effect repeated transmission of the signals, means for receiving said signals, repeating means associated with the receiver for singly printing the received repeatedly transmitted signals, relays associated with the receiver 35 repeating means adapted to supply marking or spacing current thereto, means operable upon reception of marking signals and upon reception of external disturbances of marking signal frequency for operating the relays to supply marking 40 current to the receiver repeating means, means operable upon undisturbed reception of signals of a frequency exclusive of that of the marking signals for operating said relays to supply spacing current to the receiver repeating means, and 45 means operable upon the failure to receive signals for setting the armatures of said relays to a position to supply only marking current to the receiver repeating means. 50

2. A multiple unit code telegraph system comprising means for producing marking signals of one frequency, means for producing spacing signals of a different frequency, reiterating means for controlling the operation of the signal producing means to effect repeated transmission of 55

the signals, means for receiving said signals, re-iterating means associated with the receiver for singly printing the received reiterated signals, means associated with the receiver reiterating 5 means for supplying spacing current thereto upon the reception of spacing signals and means for supplying only marking current to said receiver reiterating means upon the reception of marking signals, external disturbances and upon 10 the failure to receive any signals.

3. A multiple unit code telegraph system for simultaneously transmitting several messages through different channels by means of a single wireless transmitter, comprising means for producing a plurality of marking signals of different frequencies, means for producing a plurality of spacing signals of still different frequencies, repeating means for controlling the operation of the signal producing means to effect repeated 15 transmission of the signals, means for receiving said signals, repeating means associated with the receiver for singly printing the received repeatedly transmitted signals, relays associated with the receiver repeating means adapted to supply 20 marking or spacing current thereto, means operable upon reception of marking signals and upon reception of external disturbances of marking signal frequency for operating the relays to supply marking current to the receiver repeating 25 means, means operable upon undisturbed reception of signals of frequencies exclusive of those of the marking signals for operating said relays to supply spacing current to the receiver repeating means, and means for moving said relays to 30 a position to supply only marking current to the receiver repeating means upon the failure to receive signals.

4. A multiple unit code telegraph system for simultaneously transmitting several messages 40 through different channels by means of a single wireless transmitter, comprising means for producing a plurality of marking signals of different frequencies, means for producing a plurality of spacing signals of still different frequencies, transmitting means for controlling the signal frequency producing means of all channels to effect the transmission by the wireless transmitter at any one moment of signals of one frequency only, repeating means for controlling the operation of 45 the signal producing means to effect repeated transmission of the signals, means for receiving said signals, repeating means associated with the receiver for singly printing the received repeatedly transmitted signals, relays associated with 50 the receiver repeating means adapted to supply marking or spacing current thereto, means operable upon reception of marking signals and upon reception of external disturbances of marking signal frequency for operating the relays to supply marking current to the receiver repeating 55 means, means operable upon undisturbed reception of signals of frequencies exclusive of those of the marking signals for operating said relays to supply spacing current to the receiver repeating 60 means, and means for moving said relays to a position to supply marking current to the receiver repeating means upon the failure to receive signals.

5. A multiple unit code telegraph system comprising means for producing marking signals of one frequency, means for producing spacing signals of a different frequency, repeating means for controlling the operation of the signal producing means to effect repeated transmission of the signals, means for receiving said signals, repeating 70

means associated with the receiver for singly printing the received repeatedly transmitted signals, relays associated with the receiver repeating means adapted to supply marking or spacing current thereto, means operable upon reception of marking signals and upon reception of external disturbances of marking signal frequency for operating the relays to supply marking current to the receiver repeating means, means operable upon undisturbed reception of signals of a frequency exclusive of that of the marking signals for operating said relays to supply spacing current to the receiver repeating means, means for moving said relays to a position to supply marking current to the receiver repeating means upon the failure to receive signals, output relays associated with the receiver repeating means, and a printer connected to and rendered operable by the actuation of said output relays. 10

6. A multiple unit code telegraph system according to claim 2, in which the repeating system at the transmitter comprises a series of contact segments sub-divided into a number of sectors equal to the number of times each signal is to be transmitted, each sector containing a number of contact segments equal to the number of elements of which each signal is composed, and a movable contact member adapted to pass over the contact segments and to successively connect them to a signal transmitting relay, whereby of each group of corresponding contact segments in the different sectors, considered in a direction opposite to the direction of motion of the contact member, the first contact segment is connected through the winding of a relay to a contact of the signal transmitter, each of the following contact segments are connected through the winding of a relay with the tongue of the relay of the preceding contact segment, and the last contact segment is directly connected to the tongue of the relay of the next to the last contact segment, the tongues of the relays of all contact segments being connected to a local source of current of one polarity in one position and to a local source of current of opposite polarity in the other position. 20

7. A multiple unit code telegraph system according to claim 2, in which the repeating system at the receiver end of the communication comprises a series of contact segments sub-divided into a number of sectors equal to the number of times each signal is received, each sector containing a number of contact segments equal to the number of elements of which each signal is composed, and a movable contact member adapted to pass over the contact segments and to successively connect them in a current circuit, whereby of each group of corresponding contact segments in the different sectors, considered in a direction opposite to the direction of motion of the contact member, the first contact segment is connected through the winding of a relay to the tongue of the signal receiving relay, and each of the following contact segments are connected through the winding of a relay to the tongue of the relay of the preceding contact segment, the tongues of the relays of all contact segments but the last being connected to the tongue of the signal receiving relay in one position and to a local source of current in the other position, and the tongue of the last relay being connected to the receiving apparatus. 30

8. In a telegraph system, means for transmitting marking and spacing signals, means for receiving the marking and spacing signals, a signal translating device, means controlled by said 35

- signal receiving means upon the reception of current impulses due to external disturbances for supplying only marking currents to said translating device, means differentially responsive to the reception of spacing signals and to fading effects and means operable upon fading of the transmitted signals for causing the differentially responsive means to supply marking signals to said translating device.
- 6 9. In a telegraph system, means for transmitting marking and spacing signals, means for receiving the marking and spacing signals, a signal translating device, controlling means comprising a relay operable upon reception of signals of one character for supplying equivalent signals to said translating device, complementary means comprising a second relay operable on the reception of signals of the other character for supplying corresponding signals to said translating device, one of said relays having means in cooperation therewith operable upon reception of external impulses to supply signals of one character only, the two said relays being jointly operable on the reception of no signals and constituting means for supplying to said translating device signals of the same character as the signals produced upon reception of external impulses.
- 10 10. In a telegraph system, means for receiving marking signals of one frequency and spacing signals of a different frequency, a signal translating device, a pair of relays having armatures movable between two contacts and normally engaging one contact, the armature of the first relay being connected to said signal translating device and the armature of the second relay being connected to the normally engaged contact of the first relay, the other contact of the first relay and the normally engaged contact of the second relay being connected to a source of marking current, the other contact of the second relay being connected to a source of spacing current, means controlled by said receiving means for operating the first relay in response only to marking signals and interfering signals, and means controlled by said receiving means for operating the second relay in response to spacing, marking and interfering signals.
- 15 11. A multiple unit code telegraph system for simultaneously transmitting several messages through different channels by means of a single wireless transmitter, comprising means for producing a plurality of marking signals of different frequencies, means for producing a plurality of spacing signals of still different frequencies, means for receiving said signals, a signal translating device, relays associated with the translating device adapted to supply marking or spacing current thereto, means operable upon reception of marking signals and upon reception of external disturbances of marking signal frequency for operating the relays to supply marking current to the translating device, means operable upon undisturbed reception of signals of frequencies exclusive of those of the marking signals for operating said relays to supply spacing current to the translating device, and means for moving said relays to a position to supply marking current to the translating device upon the failure to receive signals.
- 20 12. In a multiplex telegraph system, the combination of a pair of signal circuits for transmitting independent messages, each consisting of marking and spacing currents, an outgoing channel, means controlled jointly by said signal
- circuits for supplying to said channel signaling current of one frequency upon receipt of marking current in the first circuit and spacing current in the second circuit, for supplying signaling current of a second frequency to the channel upon receipt of marking current over both circuits, for supplying signaling current of a third frequency upon receipt of spacing current in the first circuit and marking current in the second circuit, and for supplying signaling current of a fourth frequency upon receipt of spacing current in both circuits, means at a distant station for receiving the signal currents transmitted over said channel, a pair of signal translating circuits, and relays for controlling said translating circuits, and means responsive to said received signaling currents for controlling said relays so that received currents of the first frequency impress marking current on the first translating circuit and spacing current on the second, received currents of the second frequency impress marking currents on both translating circuits, received currents of the third frequency impress spacing current on the first translating circuit and marking current on the second, and received currents of the fourth frequency impress spacing current on both translating circuits.
- 25 13. In a multiplex telegraph system, the combination of a pair of signal circuits for transmitting independent messages, each consisting of marking and spacing currents, an outgoing channel, means controlled jointly by said signal circuits for supplying to said channel signaling current of one frequency upon receipt of marking current in the first circuit and spacing current in the second circuit, for supplying signaling current of a second frequency to the channel upon receipt of marking current over both circuits, for supplying signaling current of a third frequency upon receipt of spacing current in the first circuit and marking current in the second circuit, and for supplying signaling current of a fourth frequency upon receipt of spacing current in both circuits, means at a distant station for receiving the signal currents transmitted over said channel, a pair of signal translating circuits, a pair of relays having armatures movable between two contacts and normally engaging one contact, the tongue of one of said relays being connected to energize one of said translating circuits and the tongue of the other relay being connected to energize the second translating circuit, a third relay having an armature movable between two contacts and normally engaging one contact, the armature of the third relay being connected to the normally engaged contacts of the first and second relays, a source of marking current connected to the normally engaged contact of the third relay and the normally open contacts of the first and second relays, a source of spacing current connected to the normally open contact of the third relay, means responsive to received signals of the first and second frequencies singly or jointly for operating the first relay, means responsive to signaling currents of the second and third frequencies singly or jointly for operating the second relay, and means responsive to signaling currents of any of said four frequencies for operating the third relay.
- 30 14. A multiplex telegraph system comprising means for transmitting carrier wave energy, means for impressing upon said energy modulations consisting of frequencies from any one of four different tone sources, said means including two keying devices for sending marking and

- spacing signals, means for causing said keying devices when actuated independently to select a single tone frequency which represents a given one of the four possible combinations of simultaneous marking, and/or spacing signals appropriate to the two different communications channels, a receiver having four tone frequency filters of which one is a multi-frequency filter adapted to pass all of the signaling tone frequencies and the remaining filters are each adapted to pass a different frequency exclusively, means including signal responsive devices for translating the signals into separate pieces of intelligence as separately keyed at the transmitting end, and means operable under control of the all-frequency filter when it passes no signals for producing a marking signal response in each of the signal responsive devices for the different communications channels.
- 20 15. A telegraph system comprising means at a transmitting station for simultaneous keying of signals appropriate to separate communications channels, means for reiterating the transmission of each signal with others of said signals intervening, and means at a receiving station for translating the reiterated signals into a non-reiterated record of intelligence, the last said means including a device responsive alike to static impulses and to fading conditions for supplying the equivalent of a marking signal to the translating means.
- 25 16. In a telegraph system, means for transmit-

ting marking and spacing signals, said marking and spacing signals being characterized as different modulation frequencies impressed upon a carrier frequency, a reiterating system associated with said transmitting means, a receiver adapted to accept said marking and spacing signals, a filter system selectively responsive to said marking and spacing signals, a pair of relays connected to the output side of said filter system, one of said relays being adapted to respond to signals of marking frequency and the other of said relays being adapted to respond to signals of marking and spacing frequencies, a reiterating system under control of said relays, means including circuit arrangements interconnecting the contacts of said relays with sources of operating potential for causing said marking signals to be applied to said reiterating system both in accordance with the marking signals as transmitted and also in accordance with the reception of current impulses due to disturbing influences and further in response to fading conditions and further means including circuit arrangements interconnecting said sources of potential through contacts of said relay system to said reiterating system for causing spacing signals as such to be impressed upon said reiterating system.
